UNITED STATES PATENT OFFICE.

SARAH O. HENSLEY, OF KNOXVILLE, TENNESSEE.

PORTABLE ODORLESS KITCHENETTE.

Application filed April 2, 1923. Serial No. 629,464.

To all whom it may concern:

Be it known that I, SARAH O. HENSLEY, a citizen of the United States, residing at Knoxville, in the county of Knox and State of Tennessee, having invented certain new and useful Improvements in Portable Odorless Kitchenettes, of which the following is a specification.

This invention relates to improvements in what I term a portable odorless kitchenette, and particularly to a construction in which the body structure containing the kitchen utensils and provisions may be converted into an attractive article of furniture by the use of an enclosing section.

Heretofore articles of furniture of this character have been converted in appearance into other articles of furniture but the enclosing or front members thereof have constituted portions of the body structure attached thereto and of such weight and dimensions as to be difficult of operation by the ordinary housewife and expensive in construction.

The present invention seeks to provide an enclosing screen for a cabinet having an ornamental outer surface and adapted to enclose the body of the cabinet and to be retained in its relation thereto by a cover member so that the structure when assembled presents an attractive article of furniture such as a sideboard, buffet, dresser, chiffonier, or cabinet, the style of which may be modified to suit the desires or tastes of manufacturers.

Another object of the invention is to provide an improved construction of the enclosing screen comprising front and side walls with interior shelves pivotally mounted so as to be folded against the front wall when the screen is associated with the cabinet while when removed therefrom these shelves may be opened and supported within the screen in any desired position convenient for use.

Another object of the invention is the provision of a cooking compartment within the body having extending therefrom means for conducting steam and odors from the cooking vessels to an outlet, such means being detachably mounted so that the sections inside or beyond the body of the structure

may be removed and stored therein and all parts completely enclosed by the top of the cabinet body.

Other and further objects and advantages of the invention will be hereinafter set forth and the novel features thereof defined by the appended claims.

In the drawings:

Figure 1 is a perspective of the kitchenette in closed position.

Figure 2 is a section on line 2-2 of Figure 1.

Figure 3 is a detail top plan of a modified form of the screen.

Figure 4 is an elevation of the screen from its inner face.

Figure 5 is a similar view of the cabinet body.

Figure 6 is a detail section on line 6-6 of Figure 4.

Figure 7 is a similar view on line 7-7 of Figure 5.

Figure 8 is a detail section of the conducting pipe.

Figure 9 is a similar view of the collecting cone therefor.

Like numerals refer to like parts in the several figures of the drawings.

The body 10 of the kitchenette may be of any desired material or configuration and is herein shown as a rectangular structure the side walls 11 of which associated with the rear wall 12 form a series of compartments. The arrangement of these compartments may be altered at will but a desirable form is shown in which a cooking compartment 13 is provided adapted to receive a stove 14 of any desired character and beneath this compartment a shelf 15 extends for the width of the cabinet. Above this shelf a drawer 16 may be located adapted to receive cooking utensils and above this drawer a biscuit or bread board 17 is slidably mounted in the usual manner. Above the board two or more compartments 18 may be provided.

The kitchenette body is provided with a top member 19 preferably pivoted to the rear wall by hinges 20 and adapted to close the top of the kitchenette when in locked position as shown in Figure 1.

This top has a depending retaining flange 21 extending about its front and side edges

which is adapted to cooperate in the retention of the enclosing screen hereinafter described.

The cooking compartment 13 of the kitchenette is herein shown as provided with a conduit 22 for the removal of odors and steam from the vessels upon the stove 14, and this conduit is preferably formed of detachable sections suitably supported above 10 the compartment, and the section above the cabinet may be removed and stored within the cooking compartment when the kitchenette is not in use, as indicated in Figure 7. When in use this conduit may be provided 15 with a bifurcated connection 23 carrying collecting cones 24 which are disposed above the utensils upon the stove and carry all odors and steam therefrom to a suitable outlet 25 at the opposite end of the conduit. 20 This outlet may be disposed at any desired point, for instance at the top of a slightly lowered window, as indicated by dotted lines at 26 in Figure 5. The provision of 25 this conduit for removing odors and steam prevents the same from entering the room where the kitchenette is used so that the cooking in an ordinary living room may be effected without the disagreeable results usually present or any discomfort to the user 30 of the stove.

The enclosing screen for the kitchenette comprises a front wall 27 and opposite end walls 28 which may be rigidly connected together, or if desired the end walls may be 35 pivoted as shown in Figure 3. This front 27 of the screen may be ornamented or finished in any desired manner to provide an attractive article of furniture, for instance, as shown in Figure 1.

40 The doors 29 and drawers 30 are represented at the front of the screen and form in connection with the folding top 19 an attractive buffet completely concealing all of the cooking apparatus.

45 The screen is preferably provided upon its inner face with shelves 31 pivotally connected to the front wall of the screen at 32 and held in open position by chamois or flexible straps 33 which permit the folding 50 of the shelves against the inner face of the front wall in order to effect the close assemblage of the screen with the cabinet body. These shelves may be of different width and fold to overlap upon each other 55 as indicated by dotted lines in Figure 6. When the screen is assembled with the body the flanges 21 of the pivoted cover embrace the front and end walls of the screen retaining the same in its assembled position 60 as indicated in Figure 1.

In the modified form of screen shown in Figure 3 the front wall 35 thereof is provided at each end with the end walls 36 pivotally secured thereto at 37 so as to 65 swing outward therefrom as indicated by

dotted lines. In this form of the invention shelves 38 are provided within the screen, similar in construction to those described in connection with Figures 4 and 6.

70 For the purpose of providing a neat closure between the end walls of the screen and those of the cabinet the latter may be inset so that the back wall 12 of the cabinet extends beyond the end wall 11 thereof as shown at 39 in Figure 2. The cabinet and 75 also the screen may be provided with the usual rollers or casters 40 to facilitate convenient moving thereof about the room of the user.

80 In the use of the invention it will be seen that it is only necessary to raise the cover of the cabinet body when the enclosing screen which is of light construction can be very readily removed and connection made for the conduit for conducting odors 85 and steam from the cooking utensils. The shelves upon the screen may be opened and the screen located in any desired position for the convenience of the user. When it is desired to discontinue the use of the kitchenette the screen may be again associated therewith and is secured in position by simply closing the top, the flange of which overlaps the upper edge of the screen front and end sections so as to firmly retain it in 90 position and provide an attractive article of furniture.

95 The specific construction of the screen and cabinet has been herein described and shown but the invention is not confined thereto as alterations may be made without departing from the spirit thereof as defined by the following claims:

Having thus described my invention, what I claim as new and desire to secure by 105 Letters Patent, is:

1. In a kitchenette, a body section, a top member thereon, a screen having at its ends supporting means to comprise a unit separable from said section and forming the 110 front wall thereof, and means carried by said top to engage and retain the screen in associated relation with the body.

2. In a kitchenette, a body section, a top member thereon, a detached screen independent of said section and comprising front and end walls adapted to enclose said body, and means carried by the top member to embrace said walls.

3. In a kitchenette, a body section, a 120 screen having front and end walls adapted to enclose said body, and a shelf pivotally supported in said screen and adapted to fold against the front wall thereof.

4. In a kitchenette, a body section, a 125 screen having front and end walls adapted to enclose said body, a shelf pivotally supported in said screen and adapted to fold against the front wall thereof, and a flexible connection between said wall and shelf.

5. In a kitchenette, a body section adapted to contain cooking apparatus, a screen entirely detached from said body and having its front wall ornamented to represent a different article of furniture and its end walls adapted to embrace the body section, and a cover for said body adapted to engage the walls of said screen.
6. In a kitchenette, a body section provided with a cooking compartment, a detachable conduit for conducting odors therefrom, a top member pivoted upon said body section, an enclosing screen for said body provided with front and end walls, and a foldable shelf mounted upon the inner face of said enclosing screen.

In testimony whereof I affix my signature.

SARAH O. HENSLEY.
